(57) **CLAIM**

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; FIG. 7 is a front view thereof shown in an environment of use; FIG. 8 is a front exploded view thereof with a detachable middle portion of the garment, with a detachable lower portion of the garment, and with detachable sleeves of the garment shown detached; FIG. 9 is a front view thereof shown in an environment of use and with the detachable lower portion thereof shown detached and removed; FIG. 10 is a front view thereof shown in an environment of use and with both the detachable middle portion thereof and the detachable lower portion thereof shown detached and removed; FIG. 11 is a front view of the detachable middle portion of the garment of FIG. 1 shown in isolation, in an opened position, and laid flat; FIG. 12 is a front perspective view of the detachable middle portion of the garment of FIG. 1 shown folded into a pocket of the detachable middle portion and configured as a travel pillow or the like; FIG. 13 is a front view of the detachable lower portion of the garment of FIG. 1 shown in isolation, in an opened position, laid flat, and with a through-hole of the detachable lower portion in a closed position; FIG. 14 is a front view of the detachable lower portion of the garment of FIG. 1 shown folded over with the through-hole of the detachable lower portion in an opened position and configured as a scarf or the like; and, FIG. 15 is a front perspective view thereof shown with an opposite end of the detachable lower portion stuffed through the through-hole for securing the detachable lower portion in position when worn.

The portions of the garment shown in broken lines in FIGS. 1-15 do not form part of the claimed design. The broken line showing of the arms, legs, torso, and head in FIGS. 7, 9, and 10 are shown for reference only.

(Continued)

10 is for the purpose of illustrating portions of the environmental structure and forms no part of the claimed design.

1 Claim, 15 Drawing Sheets
